Fig - 6Fig - 7

FIG. 1 is a perspective view of a pedestal cottage showing our new design;

FIG. 2 is a top plan view thereof;

FIG. 3 is a front elevational view thereof;

FIG. 4 is a bottom view thereof;

FIG. 5 is a side elevational view thereof;

FIG. 6 is another side elevational view thereof; and

FIG. 7 is a rear elevational view thereof.

The short lines perpendicular to the triangular outline of the structure shown in FIG. 4 are for the purpose of illustrating the cottage floor framing.

We claim:

The ornamental design for a pedestal cottage, as shown and described.
